(57) CLAIM

The ornamental design for a printer, as shown and described.

DESCRIPTION

FIG. 1 is a front view of a printer showing my new design; FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a right perspective view thereof; and,

FIG. 8 is a left perspective view thereof.

The dash-dotted broken lines define the bounds of the claimed design; the evenly spaced broken lines form no part of the claimed design.

1 Claim, 6 Drawing Sheets
